Patented Nov. 11, 1919.

UNITED STATES PATENT OFFICE.

LARS GUST BERGQUIST, OF SHAUNAVON, SASKATCHEWAN, CANADA.

FLUE-CLEANER.

1,321,704.

Specification of Letters Patent.

Patented Nov. 11, 1919.

Application filed June 16, 1919. Serial No. 304,460.

To all whom it may concern:

Be it known that I, LARS G. BERGQUIST, a citizen of the Dominion of Canada, residing at Shaunavon, in the Province of Saskatchewan, Dominion of Canada, have invented a new and useful Flue-Cleaner, of which the following is a specification.

This invention relates to flue cleaners, and the object is to provide a device for use particularly by chimney cleaners, whereby the flues of a chimney may be thoroughly cleaned of all accumulations of soot, etc.

Another object is to provide a device of this character which may be readily introduced into the flues of a chimney and made to traverse the same from top to bottom much in the same manner as the ordinary method of cleaning chimneys, the said device being so constructed as to readily accommodate itself to flues of varying sizes, within certain limitations, and having no parts to catch or hang upon any chance projections that may be encountered within the chimney during such up-and-down movement of the cleaner.

A full and complete understanding of the invention may be obtained from a consideration of the following detailed description, taken in connection with the accompanying drawing, forming a part of this specification; it being understood that while the drawing shows a practical form of the invention, the latter is not confined to strict conformity therewith, but may be changed or modified so long as such changes or modifications mark no material departure from the salient features of the invention, as specifically pointed out in the appended claims.

Referring to the drawing, in which similar reference characters designate corresponding parts throughout the several figures;—

Figure 1 is a perspective view of the improved flue cleaning device.

Fig. 2 is a central horizontal sectional view of the same.

Fig. 3 is a central vertical sectional view of the device in position within the flue of a chimney.

In the ordinary method of cleaning flues of chimneys, a small bush, bundle of twigs or a bundle of pieces of ratan or similar material is generally used by pulling the same up and down within said flue in order to dislodge such accumulations as may be

found therein, which gravitate to the bottom of the chimney and are gathered and removed. It is necessary to be constantly renewing such bundles either in whole or in part, as the individual pieces thereof catch in projections within the flue and easily become broken, and when the bundle is thus more or less impaired, it becomes useless.

The present invention aims to provide a practically indestructible flue cleaner which will adapt itself to flues of different sizes and having cutting means which will practically scrape all four walls of a rectangular flue, thus effectually removing all accumulations encountered therein and thoroughly cleaning the same.

The device consists of four equal, flexible rings or bands 1, formed of flat, spring steel made into a continuous hoop and preferably having no seam or joint. At diametrically opposite points, approximately at the transverse center, these rings are suitably apertured for the reception of rivets 2 which are employed to secure the said rings or hoops 1 to angular securing plates, or angle irons, having wings 3 and 4, which are likewise suitably apertured for the reception of the said rivets 2, which traverse the corresponding apertures in the wings of the angular securing plates and the rings for holding the latter in position with relation to each other, in the following described novel manner:

The rings 1 are arranged in pairs, one opposite to the other and spaced apart a distance somewhat greater than the width of the largest flue that may have to be cleaned. Two pairs of equally spaced rings are thus provided which are located at right angles to each other, one corresponding side of each ring lying in overlapping relation to each of the other corresponding sides of the adjacent ring and rigidly held in such position by the angular securing plates being secured thereto by the rivets 2. The wing 3 of each angular plate is somewhat wider than the wing 4 and is adapted to be placed against the inner face of one ring, while the said wing 4 is adapted to be placed against the outer face of the next adjacent ring, as clearly shown in the drawing, thus, after being riveted, securely holding the rings each with one side overlapping upon the outside of the next adjacent ring in one direction.

The wider wing 3 is thus directed toward the center of the overlapping ring at that side and is provided with the perforations 5

into which the ends of strands 6, preferably of wire, are passed and suitably twisted or otherwise secured, as indicated at 7, the looped ends of the said strands being brought together and twisted into terminal eyes 8 and located in alignment with the center of the rectangle formed by the several rings 1. The eyes 8 are adapted to be secured to the ends of suitable wires or ropes, (not shown) for the purpose of drawing the device up and down within the flue of a chimney for the purpose of cleaning the same.

When it is desired to clean a chimney, one of the operators ascends to the top thereof and by lowering the weighted end of one of the wires or cords down the flue, the other operator may grasp the same and, as will be seen, the device may be forcibly drawn through the flue from top to bottom and back to the top again, the operation being repeated several times, until all the accumulations are removed, the flexible rings 1 expanding in an up and down direction to accommodate themselves to the different size flues and closely hugging the walls thereof in an apparent manner, and as clearly illustrated in Fig. 3 of the drawing.

In the event of there being only one operator at work, the lowermost eye 8 may be suitably weighted to provide the necessary pull downward to cause the device to repeatedly traverse the entire length of the flue.

From the foregoing it will be seen that an extremely simple and cheaply manufactured flue cleaning device has been provided which may be easily operated, which will readily adapt itself to flues of different sizes and dimensions to closely hug the interior walls thereof for removing accumulations of soot, etc., and which will not readily break or become deranged, under the severe strain to which such devices are subjected.

What is claimed is:—

45 1. A flue cleaner comprising four resilient rings or bands arranged in the form of a rectangle and disposed vertically so as to present their outer edges against the walls of the flue, and means for securing the rings or bands rigidly together at points between the tops and bottoms.

50 2. A flue cleaner comprising four resilient rings or bands arranged in the form of a

rectangle and disposed vertically so as to present their outer edges against the walls 55 of the flue, plates connecting the adjacent rings or bands, and means for raising and lowering the cleaner connected to said plates.

3. A flue cleaner comprising four resilient 60 rings or bands vertically arranged forming a rectangle, the one side of each ring placed to the outside and overlapping the adjacent side of the next succeeding ring, and means for rigidly securing the rings together at the 65 points where they overlap.

4. A flue cleaner comprising a plurality of flexible rings having a relative arrangement coinciding with the walls of a flue, and angle irons or plates secured to the abutting 70 sides of adjacent rings, and connecting them together in the form of a rectangle.

5. A flue cleaner comprising a plurality of flexible rings vertically arranged with the edge of each ring overlapping that of the 75 next succeeding ring, securing plates located at said points of overlapping, said plates comprising right-angle wings, one wing being riveted to the inner face of the adjacent portion of the inner ring and the other wing 80 being riveted to the outer face of the overlapping portion of the other ring, and means for raising and lowering the device.

6. A flue cleaner comprising four resilient rings or bands vertically arranged to form 85 a rectangle, the side of each ring placed to the outside and overlapping the adjacent side of the next succeeding ring, an angle iron located at each point of juncture and having wings one of which is riveted to the 90 outer face of the outer ring and the other wing is riveted to the inner face of the next ring and extended inwardly toward the center of the first-named ring and provided with apertures, wire strands having their 95 terminals secured in said apertures and brought above and below the device and there twisted into eyes for connection to raising and lowering ropes or strands.

In testimony, that I claim the foregoing 100 as my own, I have hereto affixed my signature.

LARS GUST BERGQUIST.
